DESIGN FOR SHAWL.

Specification forming part of Design No. 7,533, dated July 7, 1874; application filed June 27, 1874.
[Term of Patent 3½ years.]

CASE C.

To all whom it may concern:

Be it known that I, CHARLES H. LANDENBERGER, of Philadelphia, Pennsylvania, have produced or invented a Design for a Shawl, of which the following is a specification:

The nature of my design for a shawl is clearly represented by the figure in the accompanying drawing.

The groundwork of the shawl is of an uniform shade or color throughout, both for the body A, and for the borders B B and D D; and the shawl is ornamented throughout by parallel stripes; but the stripes *a b* of the borders B and D are of an uniform shade or color, differing from the shade or color of the stripes *b'* of the body, of which the stripes *b* form continuations.

A strong contrast between the body and borders of the shawl is thus presented.

Irrespective of the colors employed, or of the minor ornamentation of the stripes, I claim—

The design for a shawl, having a striped body A, longitudinally-striped borders B B, and transversely-striped borders D D, the stripes of the borders being of a shade or color differing from that of the stripes of the body, all as described, and as represented in and by the accompanying drawing.

In testimony whereof I have signed my name to this specification in the presence of two subscribing witnesses.

CHARLES H. LANDENBERGER.
